UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

CUSHION HEEL.

Application filed April 27, 1922. Serial No. 556,895.

This invention relates to cushion heels and, particularly, to heels made of rubber or other vulcanizable compositions.

One object of the invention is to produce a cushion heel which may be securely attached by machinery without the use of cement or other adhesive and will form a permanently tight joint with the heel base or the heel seat of the shoe to which it is attached.

Another object of the invention is to eliminate the metal washers which are commonly used in rubber heels to prevent the heads of the attaching nails from pulling through; and to produce a heel which may be securely attached by ordinary rubber heel nails without requiring any particular care with respect to accuracy in locating the points at which they are to be driven, while providing for separate attachment of a rubber heel and a heel base at a single nailing, to the end that when the rubber heel becomes worn, it may be replaced without disturbing the base.

In one aspect of the invention a heel is provided the main body portion of which consists of rubber or other suitable resilient cushioning material and having in its inner face an inserted member, portion or section of harder or firmer penetrable material such, for example, as canvas or other fabric, so formed as to provide an anchorage for the heads of the attaching nails which secure the rubber heel to the base and to provide space for other nails which may be driven simultaneously with the first-mentioned set for securing the base to the shoe independently of the attachment of the rubber heel.

The inserted section may advantageously be formed of a number of layers or plies of frictioned canvas which may be united to each other and to the body of the heel by vulcanization, becoming to all intents and purposes an integral part thereof. An advantageous feature of the invention consists in associating with the canvas insert breast corner tensioning members which may conveniently take the form of small, spring steel plates held between two of the layers of the laminated insert and extending well out into the breast corners of the heel. The inner face of the heel is preferably concave at the edges and the flattening of the heel

under the attaching pressure will place the 55 spring plates under tension so they will exert a permanent tendency to hold the breast corners of the heel tightly against the base.

A further advantageous feature of the invention resides in the provision of improved 60 means for facilitating the accurate location of the comparatively soft rubber heel section upon the substantially rigid base. This may conveniently take the form of registering cavities molded at predetermined 65 positions in the inner face of the rubber section, co-operating with corresponding protuberances projecting from the outer face of the rigid heel base, whereby accurate registration of the two sections 70 may be secured readily, even with unskilled labor.

Other features and advantages of the invention will be understood and appreciated from reading the following detailed description of a practical embodiment thereof 75 in connection with the accompanying drawings, in which

Fig. 1 is a perspective view of a heel embodying the invention with a portion broken 80 away to reveal the internal construction;

Fig. 2 is a fragmentary, sectional view on the plane 2—2 of Fig. 1, showing the heel attached to a shoe;

Fig. 3 is a plan view of one of the resilient 85 corner tensioning members;

Fig. 4 is a plan view of the inner face of the rubber heel;

Fig. 5 shows a central, longitudinal section of the attached heel, taken upon the 90 line 5—5 of Fig. 4; and

Fig. 6 is a view similar to Fig. 4, showing a modification.

10 indicates generally a rubber heel which may be either in the form of a half heel, as 95 shown, or a whole heel or merely a top lift. The inner face of the rubber heel is concave around the curved edge and flat in the middle while the tread face is convex around the curved edge and, likewise, flat in the middle, the thickness of the heel being substantially uniform throughout. With a heel of this conformation the use of cement in attaching the heel to a shoe is unnecessary inasmuch as the edges hug tightly against the base and produce a close joint when the portion inside of the edges is drawn down 100 and the heel held flat by the attaching nails.

A series of conical indentations 12 is formed on the tread face of the heel to indicate positions where the nails may be driven although, as will appear more fully hereinafter, it is not imperative that the nails be driven at these or any other predetermined points.

Vulcanized in, and flush with, the inner face of the heel is an insert 14 consisting of 10 three layers 16, 18, 20 of relatively firm and strong, penetrable material, such as frictioned canvas, duck or the like. The contour of the insert 14 may be varied but I have found that the contours shown in Figs. 15 4 and 6 are highly satisfactory and have certain advantages. As illustrated in Fig. 4 the insert 14 covers substantially the area in which it may be desired to insert the nails for attaching the rubber heel to the base and 20 is notched or indented, as shown at 22, at several places in its periphery to provide for base attaching nails which are not to pass through the insert. Two holes 24, are punched at predetermined places in the insert and co-operate with corresponding 25 plugs in the heel mold to locate the insert in an exactly predetermined position with respect to the heel.

A central space or opening 26 is also provided in the insert for the purpose of avoiding 30 a common difficulty resulting from the distortion of a fabric insert when it is attempted to vulcanize such insert in rubber. Under the heat and pressure of the vulcanizing 35 mold the frictioned fabric displays considerable tendency to wrinkle and "bunch up" in the center but, by providing a space as shown at 26, this difficulty is overcome and the insert adjusts itself to present a 40 smooth surface, continuous with the remainder of the inner face of the heel. In the molding process the soft rubber of the heel fills the space 26, aiding in effecting a firm, unbreakable union between the insert and 45 the soft rubber.

At each breast corner of the heel a tensioning or stiffening member in the form of a thin metallic plate 28, made preferably of 50 spring steel, is inserted between two of the plies of fabric. As herein illustrated the plate 28 is placed between the plies 16 and 18. The insertion of the plate 28, of course, occurs while the plies are being assembled prior to their vulcanization. The tensioning 55 member 28 has in its forward end a notch 30, and near its other end a hole 32, by means of which it may be exactly located upon correspondingly spaced pins in the vulcanizing mold, the holes formed in the rubber 60 heel by these pins being indicated in Fig. 2 at 34 and 36 respectively. The forward end of the plate 28 is formed at an oblique angle, as shown, providing a projecting corner 38 which extends well out into the breast corner 65 of the heel.

Additional holes 40 in the plate 38, which in Fig. 2 are shown blank to avoid confusion, are actually filled by the rubber coating of the plies 16, 18 of the frictioned fabric when the vulcanizing heat and pressure are applied. The tensioning plates are thus securely fastened in predetermined positions in the heel. One of the holes 40, is substantially in line with one of the indentations 12, as shown clearly in Fig. 2, and the hole 32 75 is substantially in line with another of said indentations. These holes in the tensioning plates 28 are materially larger than the heads of the attaching nails which, therefore, may pass freely therethrough, if desired.

In attaching the illustrated heel provision is made for driving twelve nails. Eight of these penetrate the insert 14 and are driven home until their heads are seated thereon. One of these nails is shown in Fig. 2 at 42. The other four nails, one of which is shown at 44, are driven through depressions 12 which align with the two holes 36 and two similar holes 37 (see Fig. 4) all of which are located in the notches 22 in the edge of the member 14. The nails 44 serve solely to attach the heel base 46 to the sole 48 of the shoe and have no hold upon the rubber heel. When it is desired to remove the rubber heel after it is worn, and replace it with a new one the nails 44 and the base 46 are thus left undisturbed. Although one of the base attaching nails 44 passes through the hole 32 in the tensioning plate 28 this hole is materially larger than the head of the nail and the presence of the plate therefore, does not interfere with the removal of the rubber heel.

As will be apparent, this improved heel is perfectly adapted for machine attaching. The nail drivers of the heel attaching machine may all be of the same length, in which case the heads of the nails will all be driven to the same depth, as herein illustrated, and as more fully described and explained in the copending application of Joseph H. Pope, Serial No. 509,820, filed Oct. 24, 1921. With this arrangement the heads of the base attaching nails 44 are left projecting somewhat from the surface of the heel base when the rubber heel is removed. Experience has, however, demonstrated that this does not detract from the security of the attachment of the base. Alternatively, the heel attaching machine may be provided with drivers of different lengths so that the base attaching nails will be driven more deeply than the rubber heel attaching nails and their heads seated in the upper surface of the heel base, as fully described and explained in my copending application, Serial No. 487,314 filed July 25, 1921.

The bottoms of the depressions 12 are 13 preferably imperforate and when the drivers

are withdrawn after the nails are driven the soft rubber heel 10 closes over the nail heads, as shown at 50, leaving a blind nailed heel.

My improved heel has many striking advantages, among which may be mentioned the important fact that it is perfectly adapted to be attached, either by single nailing or by double nailing, with the ordinary heel attaching machine, and no cement nor adhesive of any description is required to secure a permanently tight joint between the edges of the rubber heel and the base to which it is attached. A particularly good joint is secured at the breast corners, where the greatest difficulty is experienced with ordinary rubber heels in securing and maintaining close contact. The nails draw down the originally concave, laminated fabric insert 14 and hold it flat upon the base section 20 46. The resilient tensioning members 28 which are secured between the plies of the fabric are thus put in a state of tension and, inasmuch as they extend well forward into the breast corners of the heel, these corners 25 are permanently pressed tightly against the base and a close joint is assured.

There is an increasing tendency toward the use of rubber top lifts and rubber heel sections which are thinner than those formerly used. Under such conditions the present invention is particularly advantageous. The nail holding insert 14, being located at the inner face of the rubber heel, permits the thickness of the rubber section to be reduced 35 to a minimum, it not being necessary, as in the case of a heel provided with washers, to provide a substantial thickness of the heel material between the nail holding member and the inner face of the heel. Furthermore, the breast corner tensioning members hold the breast corners of the heel tightly 40 against the base, regardless of the thickness of the heel, a result in this respect being secured which is greatly superior to any result which can possibly be otherwise obtained 45 in securing a tight joint at the breast corners of a thin rubber heel section.

In the modification shown in Fig. 6, the fabric insert 14 is in the shape of a horseshoe and is punched with holes corresponding in position to the position of the holes 36, 37 in the heel shown in Fig. 4. The insert is located in the mold by the pins entering these holes, and the holes 25 in the heel which 55 correspond to the holes 24 in the heel of Fig. 4 are formed merely in the soft rubber of the heel.

The holes 24, or 25, in the rubber heel also serve the purpose of locating means for easily securing an exact location of the heel on the base, co-operating with corresponding projections 27 which may be molded or otherwise formed on the top lift of the base section in uniform, predetermined positions. 65 The securing of accurate registration between

the rubber heel and the base thus becomes a very simple matter, requiring no particular skill or care on the part of the heelng machine operator.

Having described the invention, what is claimed as new and desired to be secured by Letters Patent is:—

1. A rubber heel having a single inserted portion of material of sufficient strength to anchor attaching nails securely, said inserted portion being smaller in area than the heel, terminating outside of the nailing area at both the breast and rear ends of the heel, and being located in the path of only part of the attaching nails. 75

2. A rubber heel having an inserted portion of penetrable material smaller in area than the heel and of sufficient strength to anchor attaching nails securely, and having independent tensioning members at the breast corners to press said corners into firm contact with the surface to which the heel is attached. 85

3. A rubber heel having flush with its inner face an inserted member of material of sufficient strength to anchor attaching nails the paths of said attaching nails being within the general outline of said member and portions of said member in the path of a selected number of the attaching nails being 95 removed. 90

4. A cushion heel having a penetrable nail anchoring insert of firmer material than the heel body, and a separate tensioning member secured to the insert. 100

5. A cushion heel having a penetrable nail anchoring insert of firmer material than the heel body, and a tensioning member of different material from the insert secured to the insert. 105

6. A cushion heel having a laminated nail anchoring insert, and a tensioning member located between the laminae of the insert. 110

7. A cushion heel having a nail anchoring insert, and a stiffening member embedded in the insert. 115

8. A rubber heel having vulcanized therein a plurality of plies of fabric and a plurality of stiffening members vulcanized between the plies of the fabric. 120

9. A rubber heel having a nail anchoring insert embedded therein in the path of the attaching nails, the edge of said insert having notches in the path of certain of the nails, whereby the latter will not penetrate the insert. 125

10. The combination of a rubber heel having a fabric insert flush with its inner face, said insert having a plurality of holes located in accurately predetermined relation to its periphery with the aid of which holes the insert may be accurately located in a vulcanizing mold, and a rigid heel base section having corresponding protuberances projecting from its outer face, said protuberances 130

entering the holes in the rubber heel and locating the latter accurately upon the base.

nails act through the insert to place said member in a state of tension. 15

11. A shoe having a heel comprising a rigid base and a cushion heel section attached thereto by nails, the cushion section having cavities in its inner face larger than the heads of the attaching nails in which the head ends of certain of the attaching nails are located.

13. A cushion heel having a nail anchoring insert embedded therein and a tensioning member between at least a portion of the insert and the inner surface of the heel, the tensioning member having a hole larger than an attaching nail at the point where an attaching nail is to be driven and the insert being imperforate at said point. 20

12. A cushion heel having a nail anchoring insert embedded therein, and a tensioning member between the insert and the inner surface of the heel, whereby the attaching

In testimony whereof I have signed my name to this specification.

JOHN B. HADAWAY.
